UNITED STATES PATENT OFFICE.

HEZEKIAH PERRY, OF BETHEL, MAINE.

IMPROVEMENT IN BARBERS' CHAIRS.

Specification forming part of Letters Patent No. 129,423, dated July 16, 1872.

To whom it may concern:

Be it known that I, HEZEKIAH PERRY, of Bethel, in the county of Oxford and State of Maine, have invented a new and useful Barber's Chair; and I do hereby declare the following to be a full, clear, and exact description of the same, reference being had to the accompanying drawing, which is made a part of this specification, in which—

Figure 1 is a side elevation with the position of the foot-rest and operating parts when the rest is dropped, indicated in dotted lines. Fig. 2 shows a front view of the parts operating the foot-rest.

Same letters show like parts.

a shows the foot-rest pivoted at *b*, so as to move in the arc of a circle, as indicated by the position of said rest, shown in dotted lines and the seat *a'*. The foot-rest is upheld by the curved arm *c* jointed to the under side of said rest at *d*, and having a lip, or lips, like *e*. *f* is a bar extending across from one to the other of the rear legs of the chair with an edge to receive the lip or lips *e*. When the lip *e* is dropped down over the front edge of the cross-bar *f*, the rest *a* is seen supported as

in Fig. 1. This cross-bar *f* is braced by rods *h h*, which also serve as guides for the curved arc *c*. *i* is a spring attached to the front side of the cross-bar *f* and pressing under the lip *e* and arm *c*. This spring-arm *i* has a pedal, *j*, for the foot to press upon. When the foot-rest is to be dropped, the foot is pressed upon the pedal and quickly removed. Then the arm *i*, recoiling or flying up, slips up the lip *e* over the upper edge of the cross-bar *f*, and down the rest falls by its own weight and remains, until raised, in the position seen by dotted lines in Fig. 1. The rest *a* is raised either by lifting it with the hand or foot till the catch or lip *e* passes over and in front of the cross-bar *f*.

What I claim, and desire to secure by Letters Patent, is—

The combination of the foot-rest *a* pivoted at *b*, with the arm *c* pivoted to said rest at *d*, lip *e*, cross-bar *f*, spring *i*, and pedal *j*, guides or braces *h h*, all as herein set forth.

HEZEKIAH PERRY.
